US00D969819S

(12) United States Design Patent (10) Patent No.: US D969,819 S
Murphy et al. (45) Date of Patent: * Nov. 15, 2022

(54) DISPLAY SCREEN OR PORTION THEREOF WITH A GRAPHICAL USER INTERFACE

(71) Applicant: RELIAQUEST HOLDINGS, LLC,
Tampa, FL (US)

(72) Inventors: Brian P. Murphy, Tampa, FL (US);
Joe Partlow, Tampa, FL (US); Colin O'Connor, Tampa, FL (US); Jason Pfeiffer, Tampa, FL (US)

(73) Assignee: Reliaquest Holdings, LLC, Tampa, FL (US)

() Term: 15 Years

(21) Appl. No.: 29/705,948

(22) Filed: Sep. 17, 2019

(51) LOC (13) Cl. 14-04

(52) U.S. Cl.

Content Efficacy

Increase in Level of Confidence with Eligible Content not Deployed

▲ 56.90%

Increase in Level of Confidence with All Content not Deployed

▲ 173.97%

Priority	Function	Probability of True Positive	Coverage
1	Windows 10	0%	33%
2	Windows 7	0%	0%
3	Ubuntu 18.04	0%	0%
4	Ubuntu 16.04	0%	0%
5	Ubuntu 14.04	10%	0%

Likelihood of Detecting Threat

● Deployed Content Level of Confidence   ● Deployed + Eligible Content Level of Confidence   ○ All Content Level of Confidence

Recommended Rules to Increase Likelihood of Detecting Threat

Priority	Severity	Rule	Probability of True Positive	Performance Score	Kill Chain Phase
1	Low	Threat File High Detected	50%	74	3 - Post-Exploit
2	Medium	Threat File High Detected	50%	74	3 - Post-Exploit
3	Medium	SharePoint File Shared Outside Organization	100%	50	4 - Persistence
4	Medium	SharePoint File Shared Outside Organization	100%	50	4 - Persistence
5	Medium	Hidden File Present	10%	60	5 - Actions on the Objective
